CLAIM

The ornamental design for a shoe as shown and described.

DESCRIPTION

FIG. 1 is a bottom view of a shoe showing my new design; FIG. 2 is a rear bottom perspective view thereof; FIG. 3 is a front bottom perspective view thereof; and, FIG. 4 is an opposite front bottom perspective view thereof. The broken lines depicting the remainder of the shoe form no part of the claimed design. The unshaded areas form no part of the claimed design.
